DRAGLINE BUCKET

Harold J. Atkins and Charles M. Conner,
Chicago, Calif.

Application June 14, 1937, Serial No. 148,206

2 Claims. (Cl. 37—136)

This invention relates to drag line buckets and has for an object to provide a novel lid for fully closing the forward or loading end of the bucket so as to enable the operator to hold the bucket full of any kind of material at an angular pitch of 45° or more.

A further object is to provide a novel lid and operating mechanism therefore which will permit a full bucket being picked up at any point between the machine and the end of the boom and which will permit of articles too large to go into the bucket, such as stumps, logs, stone, ore, coal and so forth being picked up by clamping the lid against the article after the bucket is dragged under the article.

A further object is to provide a device of the class described which may be formed of a few strong simple and durable parts, which will be inexpensive to manufacture, and which will not easily get out of order.

With the above and other objects in view the invention consists of certain novel details of construction and combination of parts hereinafter fully described and claimed, it being understood that various modifications may be resorted to within the scope of the appended claims without departing from the spirit or sacrificing any of the advantages of the invention.

In the accompanying drawings forming part of this specification,

Figure 1 is a side elevation of the bucket showing the lid held closed by the hoist cable while the drag line is held taut, preparatory to dumping the bucket.

Figure 2 is a side elevation of the bucket showing the same dipped downward to dumping position upon slackening of the drag line, the trip chain tightening as the bucket is tipping downward to open the lid wide open and hold the same open when the bucket is in dumping position.

Figure 3 is a side elevation of the bucket showing the parts after loading and with the lid closed by tension of the hoist cable preparatory to elevating the bucket to dumping position.

Figure 4 is a plan view of the bucket and lid shown in Figure 3.

Figure 5 is a detail sectional view taken on the line 5—5 of Figure 4 with the lid and other parts removed.

Referring now to the drawings in which like characters of reference designate similar parts in the various views, 10 designates a drag line bucket having the usual cutting teeth 11 at the front end thereof. Suitable brackets 12 are secured to the rear ends of the side walls of the bucket and

have chains 13 connected thereto, the chains being connected to a link 14 which in turn is connected to the hoist cable 15 of a derrick boom 16 for raising and lowering the bucket.

The novel feature of this invention resides in the lid and hoist power controlling means therefore for automatically closing the forward or loading end of the bucket each time it has been loaded and is being elevated to transport the material to any predetermined point between the machine and the end of the boom, the lid being held fully closed by the hoist cable and thereby increasing the efficiency and capacity of the bucket.

Said means consists preferably in the provision of a lid 17 adapted to form a closure for the front of the bucket and being of hoe-like contour. The lid is provided with a pair of spaced arms 18 which extend from the top of the lid at the sides thereof rearwardly toward the top of the bucket and are pivotally connected to the top of the bucket side walls intermediate the ends thereof by pivot pins 19 which are carried in brackets 20 which are mounted on said side walls. The arms 18 are formed integral with lever arms 21 which are inclined upwardly toward the front of the bucket as shown best in Figure 3 and at the upper ends are bent inwardly as shown at 22 in Figure 4, to converge toward each other and thence are terminally bent parallel to provide terminals as shown at 23 to receive between them the end of a trip cable 24 which latter is firmly secured in place by a bolt 25 passed through an eye 26 formed on the cable.

The trip cable 24, as best shown in Figure 1, extends forwardly toward the front end of the bucket where it passes over a sheave 27 which is carried by arcuate bracket arms 28 which extend upwardly from the front ends of the side walls of the bucket. The trip cable thence passes over a sheave 29 carried by the aforementioned link 14 and is terminally secured to the conventional drag line 30 by a ring 31, as best shown in Figure 1.

To the same ring a pair of cables 32 are secured and form a part of the trip cable, these cables passing over sheaves 33 which are mounted on the side walls of the bucket near the rear ends thereof and these cables are adjustably secured to the lever arms 21 by respective clevises 34 which are selectively receivable in a row of openings 35 formed in the lever arms 22.

A pair of drag chains 36 are secured to the ring 31 and at the rear ends are secured to bolts 37 carried by brackets 38 that project from the front edges of the side walls of the bucket. When

loading, the initial pull of the drag line pulls the cables 32 forwardly and rocks the lever arms 22 of the lid rearwardly toward the rear wall of the bucket and thereby elevates the lid 17 and holds the same elevated and during further pull the drag chains 36 are tensioned to pull the bucket forward through the material to be loaded.

After loading when the drag line is held slightly taut and simultaneously the hoist cable is pulled, the cables 24 are pulled rearwardly and rock the lever arms 22 of the lid forwardly to close the lid and hold the lid held tightly closed to retain a full load while the bucket is being elevated. It will be observed by referring to Figure 1 that the full bucket may assume an angular position of 45° or more without spilling any of the contents.

A trip chain 39 is secured to the upper ends of the lever arms 21, as best shown in Figure 3, and is secured to an eye 40 at the lower end of the beforementioned link 14 to which same eye the beforementioned hoist chains 13 are secured. When the bucket 10 is over the desired place upon which the load is to be discharged, the operator slacks off the drag line 30 whereupon the front end of the bucket will dip downward while the trip chain 39 becomes taut and moves the lever arms 22 to swing the lid to full open position and hold the lid in this position while the load is being dumped and until the bucket has been lowered to the ground to again be filled.

From the above description it is thought that the construction and operation of the invention will be fully understood without further explanation.

What is claimed is:

1. The combination with a drag line bucket having an open front end, of a hoe-like lid closing the front end of the bucket and having a shank pivotally connected to the bucket substantially midway between the front end and the rear end of the bucket, a lever extending upwardly from the shank for rocking the lid to open and to closed position, a drag line connected to the front of the bucket, a lifting cable connected to the rear of the bucket, a trip cable connected with the drag line and having a slip connection with the lifting cable, a bracket arm carried by and extending above the front end of the bucket, a direction changing sheave carried by the upper end of the bracket arm, a direction changing sheave

carried by the bucket near the rear end thereof, said trip cable being trained over the first named sheave and terminally connected to the lever for rocking the lever to close the lid when the hoist cable is tensioned, a second cable connected to the drag line and trained over the sheave at the rear end of the bucket and terminally connected to the lever intermediate the ends thereof for rocking the lever to hold open the lid when the drag line is tensioned and the hoist cable is slackened, and a trip chain connected to the hoist cable and to said lever and adapted to be tensioned to pull open said lid when the drag line is slackened and the hoist cable is held tensioned to permit dumping of the bucket.

2. The combination with a drag line bucket having an open front end, of a hoe-like lid closing the front end of the bucket and having a shank extending rearwardly along the top of the bucket, means pivotally connecting the end of the shank to the top of the bucket substantially midway between the ends of the bucket, a lever connected to said shank and extending obliquely upward above the bucket, a drag line connected to the front end of the bucket, a lifting cable connected to the rear end of the bucket, a trip cable connected with the drag line and having a slip connection with the lifting cable, an upwardly extending arched bracket arm connected to the sides of the bucket at the front end of the bucket, a sheave mounted on the arm at the top thereof and disposed at substantially the height of the top of said lever, a second sheave mounted on the bucket near the rear end of the bucket, said trip cable being trained over the sheave carried by the bracket arm and being terminally connected to the top of the lever for closing the lid when the hoist cable is tensioned, a second cable connected to the drag line and trained over said sheave at the rear end of the bucket and being terminally connected to said lever intermediate the ends thereof for rocking the lever to hold open the lid when the drag line is tensioned and the hoist cable is slackened, and a trip chain connected to the hoist cable and to said lever and adapted to be tensioned and pull open said lid when the drag line is slackened and the hoist cable is held tensioned to dump the bucket.

HAROLD J. ATKINS.
